RAILWAY TRAFFIC CONTROLLING
APPARATUSEarl M. Allen, Swissvale, Pa., assignor to The
Union Switch & Signal Company, Swissvale,
Pa., a corporation of Pennsylvania

Application January 9, 1935, Serial No. 1,007

20 Claims. (Cl. 246—134)

My invention relates to railway traffic controlling apparatus, and more particularly to electrically interlocked apparatus for governing or controlling the signals and switches of a track layout having a plurality of traffic routes.

One object of my invention is to eliminate the usual electro-mechanical locking of the control levers by which the dispatcher or operator controls the switches and signals, by providing a system of relays having interconnected circuits and controlled by levers in the dispatcher's office which are free to be operated at any time. A particular feature of my invention resides in the provision of means whereby a signal lever may be operated to clear a signal for a route at the same time the switch control levers are operated to set up the route, and the signal will be prevented from clearing until each switch of the route governed by the signal agrees as to position with its switch control means. Another object of my invention resides in the provision of means for preventing interference with any signal which is at clear, by the operation of the switch control means for any switch of its route or by the operation of the signal control means for an opposing or conflicting signal. Other objects and features of my invention will appear as the description proceeds.

I will describe one form of apparatus embodying my invention, and will then point out the novel features thereof in claims.

Referring to the accompanying drawings, Fig. 1 illustrates diagrammatically the switches and signals of a typical track layout which the apparatus of my invention is adapted to control. Figs. 2 to 12, inclusive, when taken together, constitute a diagrammatic view of one form of the apparatus of my invention arranged for governing the switches and signals of the track layout of Fig. 1.

Similar reference characters refer to similar parts in each of the several views.

Referring to Fig. 1, while a specific track layout is disclosed, it is to be understood that the apparatus of my invention is adapted to control other track layouts that may involve entirely different combinations of switches and signals, the relatively simple layout shown, however, being adequate to illustrate the principles of my invention. Fig. 1 illustrates by a single line diagram each of the two main tracks of a double track railway connected by a crossover comprising the switches 1 and 1A, the upper track being also connected to a siding by a single switch 3. The movement of traffic over the switches is governed by the signals bearing the references 2 and 4 with distin-

guishing prefixes R and L indicating the direction of traffic governed by the signals. It is to be understood that the rails of the tracks are divided into sections by insulated joints, the main track sections including the switches, and extending from one of a pair of opposing signals to the other, being indicated by the references 1T and 3T, respectively, while the adjoining approach sections are indicated by the references 2T, A2T, 4T and A4T, respectively. Each section is provided with the usual closed track circuit including a normally energized track relay in accordance with standard practice, as indicated diagrammatically in the drawings, each track relay being identified by the reference letter R with a prefix indicating the track section. The switch sections 1T and 3T also each have a slow pickup slow release relay TZ associated therewith.

In order to simplify the drawings and to enable the circuits to be more readily traced, I have identified each relay contact by a number and each relay by a letter with distinguishing prefix or suffix including a number identifying the switch or signal with which the relay is associated, those contacts not adjacent the respective relays which operate them bearing the reference characters for the respective relays as well as numbers identifying the contacts. Furthermore, instead of showing the source of current for energizing the relays and the wires leading thereto in detail, I have shown only the terminals of the source, which I have designated by the reference character B, referring to the positive or supply terminal, and by the reference character C, referring to the negative or common terminal. Thus, referring to Fig. 2, the circuit for relay 1TZ may be traced from one terminal B of the source of current, front contact 5 of track relay 1TR, relay 1TZ to the other terminal C of the same source, this circuit being opened when relay 1TR is shunted due to the occupancy of section 1T by a train.

Each of the switches 1, 1A and 3 is actuated by a power operated switch machine of the dual selector type identified in Fig. 1 by the references 1SM, 1ASM and 3SM, respectively. Each switch machine is provided with a motor having an operating circuit controlled by contacts of a polarized relay WR and similar to the motor circuit for switch 1 shown in Fig. 3. These polarized switch control relays are shown in Fig. 4, and are controlled by the track relays TR and their repeaters TZ for the switch sections, by the approach locking relays M shown in Fig. 6 and by the manually governed switch control relays NWS and RWS of Fig. 11, polarized relay 3WR for

switch 3 being also controlled by the section locking relay 3S of Fig. 7. Each switch machine is provided with the usual circuit controller, which may, for example, be of the type disclosed in the Zabel Patents Nos. 1,293,290 and 1,413,820, for controlling those contacts identified in the drawings by the reference SM, such as the motor cut-out contacts of Fig. 3, and the indication contacts for controlling the switch indication relays 10 KR of Fig. 5.

Referring to Fig. 3, the motor circuit for operating the switch to its normal position may be traced from one terminal B of the source of current, front contact 6 and normal polar contact 15 7 of relay 1WR, armature m of the switch operating motor, normal polar contact 8 of relay 1WR, contact 13 of the circuit controller of switch machine 1SM, field 14 of the motor to the other terminal C of the source, the circuit 20 being opened by contact 13 when the switch moves to its normal position. The reverse operating circuit is similar but includes the reverse polar contacts 8 and 7 of relay 1WR and contact 15 of 1SM which opens when the switch 25 moves to its reverse position.

Referring to Fig. 4, the normal energizing circuit for relays 1WR and 1AWR may be traced from terminal B, front contact 16 of switch control relay 1NWS, contacts 17, 18, 19, 20, 21, 22 30 of the various approach locking and track relays as indicated on the drawings, relays 1WR and 1AWR in multiple, contacts 23 and 24 of relays 1TZ and 3TZ, back contact 25 of relay 1RWS to terminal C. The reverse energizing circuit 35 for relays 1WR and 1AWR is similar but includes front contact 25 of relay 1RWS and back contact 16 of relay 1NWS.

Relay 3WR is similarly controlled by contacts 26 and 27 of the switch control relays 3NWS 40 and 3RWS, as is obvious from the drawings. It will be clear from the foregoing that the circuits for each of the relays WR are so arranged that the relay will not respond to an operation of one of its control relays NWS or RWS unless conditions are favorable for the operation of the switch.

Each switch machine is provided with a dual selector lever which may be moved either to a "motor" position to couple the switch operating mechanism to the motor of the switch machine to condition the switch for power operation, or to a "hand-throw" position to uncouple the motor and to condition the switch for hand operation by the train crew. When in the "hand-throw" position, the dual selector lever opens the contacts DS of Fig. 11 to deenergize the switch control relays NWS and RWS to maintain the motor circuits open until the dual selector lever is restored and one of the switch control 55 relays is reenergized by the dispatcher or operator, and also opens the contacts DS of Fig. 5 to deenergize the indication relay KR and to thereby open the signal circuits, as hereinafter described, while the switch is conditioned for hand operation.

Referring to Fig. 5, the normal energizing circuit for the polarized indication relay 1KR may be traced from terminal B, contacts 28 and 29 70 controlled by the dual selector levers 1DS and 1ADS of switch machines 1SM and 1ASM, contacts 30 and 31 of the circuit controllers for switch machines 1ASM and 1SM, relay 1KR, contacts 32 and 33 to terminal C. The reverse 75 energizing circuit for relay 1KR may be traced

from terminal B, contacts 28, 29, 34, 32, relay 1KR, contacts 31 and 35 to terminal C. The circuits for relay 3KR are similar but include the dual selector and indication contacts of switch machine 3SM only, as is obvious from the drawings. It is to be understood that each indication relay KR will be energized in a position corresponding to that of the switch only when the switch points are closed and locked by the switch machine, and in the case of the crossover, when both switches 1 and 1A occupy corresponding positions.

Each indication relay KR has a pair of repeating relays NKP and RKP also shown in Fig. 5, each relay NKP or RKP being energized by an obvious circuit including contacts such as 36 and 37 closed when the corresponding relay KR is energized in its normal or reverse direction, respectively. These repeating relays provide additional indication contacts for controlling the approach locking relay circuits of Fig. 6 and the signal relay circuits of Fig. 9 as hereinafter described, and together with the switch control relays NWS and RWS control the relays 1NKZ, 1RKZ and 3KZ of Fig. 5 in such a manner that each relay KZ is energized only when the switch has completed its movement to the position to which it is operated by the energized switch control relay. The relays KZ control the route locking circuits of Fig. 10, the circuit requirements 30 being such that but one relay 3KZ is required for switch 3 while two relays are required for the crossover. Relay 3KZ is energized over a circuit from terminal B, contacts 38 and 39, relay 3KZ to terminal C when switch 3 is normal and 35 the normal control relay 3NWS is energized, or over the circuit from terminal B, contacts 40 and 41, relay 3KZ to terminal C when switch 3 is reversed and relay 3RWS is energized. Relay 1NKZ is energized over a circuit from terminal B, contacts 42, 43, relay 1NKZ to terminal C, when switches 1 and 1A are normal and relay 1NWS is energized, while relay 1RKZ is energized over a similar circuit including contacts 44 and 45 when switches 1 and 1A are reversed and relay 1RWS is energized.

Referring now to Fig. 6, an approach locking relay M is provided for each direction for each main track, the circuits of these relays being generally similar to those disclosed in the Wallace Patent No. 1,959,072. Relay R2M for example, is normally energized when signal R2 indicates stop by a circuit which may be traced from terminal B, back contacts 46 and 47 of the signal relays RA2H and RB2H, front contact 48 and 55 winding of relay R2M to terminal C. If one of these signal relays is energized to clear the corresponding signal, relay R2M is released. If the signal is then put to stop manually, relay R2M will pick up over the circuit including contacts 60 46 and 47 and front contact 49 of relay A2TR provided there is no train approaching signal R2 and approach section A2T is unoccupied. In the event the approach section is occupied, however, putting the signal to stop will complete a 65 circuit from terminal B, back contacts 46, 47, 48, front contact 50 of relay 1TR, time element relay 2TE to terminal C. Relay 2TE will become energized and after a predetermined time interval will close contact 51 to pick up relay R2M. If 70 signal R2 is put to stop automatically by the passage of a train and switch 1 is normal, relays 1TR, 1TZ and 2TR will become released and relay R2M will be picked up when the train enters the receding approach section 2T by the 75

circuit including back contact 52 of relay 2TR, back contact 53 of reverse indication relay 1RKP, and back contact 54 of relay 1TZ. If signal R2 is put to stop automatically by the passage of a 5 train and switch 1 is reversed so that relay 1RKP is energized, relays 1TR, 1TZ, 3TR and 3TZ will become released and relay R2M will be picked up when the train enters section 3T by the circuit including back contact 55 of relay 3TZ, front 10 contact 53 of relay 1RKP and back contact 54 of relay 1TZ.

The circuit for the remaining approach locking relays L2M, R4M and L4M are generally similar and may be readily traced from the drawings. It 15 will be noted, however, that the approach release circuit for relay L4M includes a front contact 56 of indication relay 3NKP which is open when switch 3 is reversed so that when signal LC4 is put to stop manually the release of the locking is effected only by operation of the time element relay 20 4TE, there being no approach track circuit for the siding.

From a consideration of the circuits of Figs. 4 and 6, it will be clear that the switches 1 and 1A 25 of the cross-over are approach locked when a signal has been cleared for a train approaching from either direction on either main track or on the siding by one of the relays M and that the switches are locked by the release of the track 30 relays R when the train accepting the signal occupies section 1T or 3T, and that switch 3 is similarly locked by the relays M and R of the upper track only. Switch 3 is however also locked by the release of relay R2M or of 1TR when the 35 crossover is reversed, by means of the section locking relay 3S.

Referring to Fig. 7, a circuit may be traced from terminal B, front contact 57 of relay R2M, front contact 58 and winding of relay 3S to terminal C, 40 which circuit opens to release relay 3S when relay R2M is released by the clearing of arm b of signal R2 for a movement over the crossover reversed and over switch 3. When a train accepts this signal, relay R2M becomes energized but relay 45 3S does not pick up as long as the train occupies section 1T by reason of contact 60 of relay 1TR which is included in the circuit of relay 3S in multiple with contact 58. When the crossover is normal, contact 59 of relay 1NKP shunts contact 50 57 and maintains relay 3S energized independently of relay R2M. The control effected by relay 3S is thus such that switch 3 is locked not only when the crossover is reversed and arm b of signal R2 has been cleared, but also if a train passing 55 that signal occupies either section 1T or 3T, while if a signal is cleared for a train moving in the opposite direction over switch 3, relay 3S remains energized and the locking is released as soon as the train leaves section 3T.

60 The signals shown in Fig. 1 may be of any suitable type and in practice those signals governing high speed routes will generally be three-position signals governed in accordance with the condition of other signals in advance, not shown herein, in addition to being subject to manual and track circuit control. To illustrate the present invention, however, it is deemed sufficient to assume merely that each signal indicates proceed or clear when energized and indicates stop when deenergized. A signal relay H is provided for each signal arm, and each signal relay H controls a lighting circuit for the signal as well as the locking circuit for the switches in the routes governed by the signal as above described.

75 Referring to Fig. 8, the diagram at the left

shows the lighting circuits for the high speed signal represented by arm a of signal R2 by means of which a green lamp G is lighted when signal relay RA2H is energized and front contact 161 is closed, and by which a red lamp R is lighted 5 when the signal relay is deenergized, these circuits being obvious from the drawings.

The lighting circuits for arm a of signal R4 are similar but are controlled by relay LA4H. The diagram at the right of Fig. 8 shows the lighting 10 circuits for the slow speed signal L2 controlled by signal relay L2H and differ from the one described only in that a yellow lamp Y is lighted 15 when the signal relay is energized. The remaining signals are also slow speed signals and have 20 lighting circuits similar to those for signal L2.

The signal relays H are controlled over the signal relay network of Fig. 9, the circuit for each signal relay H being controlled by front contacts of a route relay HX for the corresponding signal 20 and by a back contact of a route relay HX for an opposing signal. The signal relay network is a counterpart of the track layout and includes a circuit for each direction for each route through the layout, each circuit being formed by conductors corresponding to portions of the track which are connected together by indication contacts controlled in accordance with the positions of the track switches. The route circuit for each signal 25 includes a front contact of the approach locking relay M associated with the opposing signal, thereby not only insuring that a signal can not be cleared unless the opposing signal indicates stop, but also interposing a time delay in the reversal of the direction of traffic when a signal is 30 put to stop in the face of an approaching train.

Assuming that switches 1 and 1A are normal and sections 1T and 2T unoccupied, if relay R2HX is picked up and relay L2HX is released, relay 40 RA2H will be energized over the circuit from terminal B, contact 61 of relay L2M, back contact 62 of relay L2HX, contacts 63, 64, 65, 66, 67, relay RA2H, contact 68 to terminal C. If relay L2HX is picked up and relay R2HX is released, relay 45 L2H will be energized independently of track conditions over the circuit from terminal B, contact 69 of relay R2M, contacts 64, 63, front contact 62, relay L2H, contact 70 to terminal C.

When switches 1 and 1A are normal, relay L4HX or R4HX may be picked up at the same time as 50 relay L2HX or R2HX. If relay L4HX is picked up and relay R4HX is released, and sections 3T and 4T are unoccupied and switches 1, 1A and 3 are normal, relay LA4H will be energized over the circuit from terminal B, contact 71 of relay 55 R4M, contacts 72 to 79, inclusive, relay LA4H, contact 80 to terminal C, while if switch 3 is reversed, relay LC4H will be energized independently of track conditions provided the circuit from terminal B, contact 71 of relay R4M, contacts 72 to 75, inclusive, contact 81 of relay 3RKP, relay LC4H, contact 80 to terminal C. Likewise, if relay R4HX is picked up and relay L4HX is released, relay 60 R4H will be energized independently of track conditions provided switch 3 is locked either normal or reverse over the circuit from terminal B, contact 82 of relay L4M, contacts 75, 74, 73, 72, relay R4H, contact 83 to terminal C.

Assuming that switches 1 and 1A are reversed, relay R2HX or L4HX may be picked up. If 70 relay R2HX is picked up and relay L4HX is released, and sections 1T and 3T are unoccupied and switch 3 is reversed, relay R2H will be energized over a circuit from terminal B, contact 75 of relay L4M, contacts 75, 74, contact 84 of 75

Referring to Fig. 8, the diagram at the left

relay 1RKP, contacts 64, 65, contact 85 of relay 3RKP, contacts 86, 87, relay RB2H, contact 68 to terminal C. Relay RB2H will also be energized if switch 3 is normal and section A4T unoccupied 5 over a circuit similar to that just traced but including contact 88 of relay A4TR instead of contact 85.

If relay L4HX is picked up and relay R2HX is released, and switches 1, 1A and 3 are reversed, 10 relay LC4H will be picked up over the circuit from terminal B, contact 69 of relay R2M, contacts 64, 84, 74, 75, 81, relay LC4H, contact 80 to terminal C.

If relay L4HX is picked up and relay R2HX is released, and switches 1 and 1A are reversed and switch 3 is normal, and if sections 1T and 3T are unoccupied, relay LB4H will be energized over the circuit from terminal B, contact 69 of relay R2M, contacts 64, 84, 74, 75, 76, 77, 89, 90, 20 relay LB4H, contact 80 to terminal C.

The circuits for the route relays HX which control the signal relay circuits just traced are shown in Fig. 10. Each route relay HX is a stick relay having a pickup circuit including front contacts of a manually governed signal control relay LHS or RHS, shown in Fig. 11, each pickup circuit including in series the winding of a lock-out relay LO. These circuits are arranged in a network formed by conductors interconnected by 25 contacts of the relays KZ of Fig. 5, each of which contacts is closed only when the respective switch and its control relay are in correspondence. Each route relay HX is thus energized in series with a lockout relay LO over a route circuit when the corresponding signal control relay is energized as soon as each switch of the route assumes the position to which it has been last operated. Each lockout relay LO when energized opens its back contact shown in Fig. 11 and included in the 40 pickup circuit of the signal control relay HS for the opposing signal and serves to prevent interference with a signal that has been cleared if the operator attempts to clear the opposing signal.

The route network of Fig. 10 also includes normally closed checking contacts 93 and 101 of the time element relays TE of Fig. 6, to insure that these relays are in their normal position when a signal is cleared and will thus be in their proper 50 position to effect a time release of the locking when a signal is put to stop manually.

Assuming that the switch control relay 1NWS is energized and switches 1 and 1A are normal, contacts 94 and 100 of relay 1NKZ will be closed. 55 If relay R2HS is picked up and relay L2HS is released, relays R2HX and L2LO will be energized over the circuit from terminal B, contact 81 of relay R2HS, relay R2HX, front contact 92, contacts 93, 94, back contact 95, relay L2LO to terminal C. If relay L2HS is picked up and relay R2HS is released, relays L2HX and R2LO will be picked up over the similar circuit from terminal B, front contact 97 of relay L2HS, relay L2HX, contacts 95, 94, 93, 92, relay R2LO to terminal C. Assuming further that relay 3KZ is 65 energized, if relay R4HS is picked up and relay L4HS is released, relays R4HX and L4LO will be energized over the circuit from terminal B, front contact 98 of relay R4HS, relay R4HX, contacts 99 to 103, inclusive, relay L4LO to terminal C. If relay L4HS is picked up and relay R4HS is released, relays L4HX and R4LO will be picked up over the similar circuit from terminal B, front contact 104 of relay L4HS, relay L4HX, contacts 70 103, 102, 101, 100, 99, relay R4LO to terminal C.

Assuming that relays 1RKZ and 3KZ are energized, if relay R2HS is picked up and relay L4HS is released, relays R2HX and L4LO will be energized over the circuit from terminal B, front contact 91 of relay R2HS, relay R2HX, contacts 92, 93, 105, 101, 102, 103, relay L4LO to terminal C. If relay L4HS is picked up and relay R2HS is released, relays L4HS and R2HS will be energized over the circuit from terminal B, front contact 104 of relay L4HS, relay L4HX, contacts 10 103, 102, 101, 105, 93, 92, relay R2LO to terminal C.

Each relay HX, when energized as above described, will complete a stick circuit including the front contact of the associated signal control relay, but independent of the route network, which serves to hold the relay energized to insure that a signal can not be put to stop inadvertently by the release of a relay KZ due to the operation of a switch control relay for any switch 20 of a route governed by the signal. Each stick circuit is similar to that for relay R2HX, which circuit may be traced from terminal B, front contact 91 of relay R2HS, the winding and front contact 96 of relay R2HX, resistor 106 to terminal C. Each resistor such as 106 is proportioned so as to limit the current through the stick circuit to prevent releasing the lockout relay LO which is in shunt with the resistor when the route circuit is closed, but to permit sufficient 30 current to flow to maintain the route relay HX energized when the route circuit is open.

The switch and signal control relays NWS, RWS, LHS and RHS may be controlled in any desired manner, either by direct wire connection 35 to the contacts of switch and signal levers in a remotely located control office, or by means of a selective communication system of any suitable type, provided, however, apparatus functioning in a manner similar to that herein disclosed, is included between the control levers and the relays to prevent at times the response of the relays to lever operations. One type of communication system suitable for controlling the apparatus of my invention is that disclosed and claimed in a 45 United States application for Letters Patent by Lloyd V. Lewis, for Remote control systems, Serial No. 600,786, filed March 23, 1932. This system is described in the Book entitled "Centralized Traffic Control System—Time Code Scheme, 50 Manual No. 502, September 1931", published by The Union Switch & Signal Company, Swissvale, Pa.

In Fig. 11, I have shown circuits for the switch and signal control relays by means of which the 55 manual control of the switches and signals is effected, as arranged for control by the delivery relays D and by contacts 9 to 12, inclusive, which contacts are to be understood as being contacts of the selector relays 9 to 12, inclusive, of the time 60 code scheme of the Lewis application. As described in the book referred to, each control code includes station selecting elements for selecting and operating one delivery relay or another momentarily at the end of the code, and also includes switch control elements which are effective to selectively close contact 9 or 11, depending upon whether a switch control lever SW for the switch corresponding to the operated relay D is in its normal or reverse position. In addition, 70 each control code includes signal control elements which are effective to selectively close contact 10 or 12 if a three-position signal lever Sig. associated with such switch lever has been moved to its left-hand or to its right-hand position for 75

clearing the signal for the corresponding direction, while contacts 10 and 12 both remain open when the delivery relay D is operated if such signal lever is in its stop position. It is to be understood, therefore, that contacts 9 to 12, inclusive, are operated in accordance with lever position as illustrated diagrammatically by dotted line connections on the drawings, and then relay 1D or 3D, as the case may be, is selected and operated momentarily by code. It is evident from the drawings that each pair of switch control relays NWS and RWS is arranged so that one relay or the other may be picked up by a momentary impulse when the corresponding delivery relay D is energized, provided the selector contact 9 or 11, respectively, is closed, the energized relay thereafter being maintained picked up by means of a stick circuit including a back contact of the delivery relay. Each delivery relay D and selector contacts 10 and 12 similarly controls a pair of signal control relays LHS and RHS, the circuits herein disclosed differing from those described in the book in that the circuits of the signal control relays include contacts of the lockout relays of Fig. 10, which function to prevent interference with a signal that has been cleared by an attempt to energize the signal control relay for the opposing signal.

The relays MP, shown in Fig. 12, have contacts in the pickup circuits for the switch control relays which serve to prevent at times, the response of the switch control relays to code signals transmitted from the dispatcher's office, but these circuits differ somewhat from the corresponding circuits of the relays MP described in the book. Referring to Fig. 12, a circuit for relay 1MP may be traced from terminal B, contacts 107, 108, 109, 110 of the approach locking relays M, relay 1MP to terminal C. Relay 1MP will be deenergized when any one of the signals 2 or 4 is cleared, but will pick up when a train accepts the signal and occupies the corresponding switch section, due to the closing of back contact 111 of relay 3TZ or back contact 112 of relay 1TZ. The circuit for relay 3MP may be traced from terminal B, contacts 107 and 108 of the approach locking relays M for the upper track, contact 113 of relay 2S, relay 3MP to terminal C. Relay 3MP will be deenergized when any one of the signals 4 or arm b of signal R2 is cleared but will pick up when a train accepts the signal and enters the corresponding switch section due to the closing of back contact 111 of relay 3TZ or back contact 114 of relay 1TZ.

Referring now to Fig. 11, assuming that delivery relay 1D picks up momentarily while selector contact 9 is closed and that relays 1MP and 3MP are energized and also that the dual selector levers 1DS and 1ADS are in the motor position so that contacts 118 and 119 are closed, a pickup circuit for relay 1NWS will be closed from terminal B, contact 9, contact 115 of relay 1D, contacts 116 and 117 of relays 1MP and 3MP, relay 1NWS, contacts 118 and 119 to terminal C. When relay 1D releases, a stick circuit for relay 1NWS is closed from terminal B, back contact 120 of relay 1D, back contact 121 of relay 1RWS, front contact 122 and winding of relay 1NWS, contacts 118 and 119 to terminal C, to maintain relay 1NWS energized until relay 1D is again operated. If relay 1D is operated when the pickup circuit of relay 1NWS is open, relay 1NWS will become released due to the momentary opening of contact 120. The pickup circuit of relay 1RWS may be traced from terminal B, selector contact 11, contacts

123, 124, 125, relay 1RWS, contacts 118 and 119 to terminal C, while its stick circuit which functions in a manner similar to that for relay 1NWS may be traced from terminal B, contacts 120, 126, 127, relay 1RWS, contacts 118 and 119 to terminal C. Each MP contact in the pickup circuit of relays NWS and RWS is shunted by a front contact of the indication relay NKR or RKR for the corresponding position of the switch in the manner shown in the H. S. Young Patent No. 1,974,439, issued Sept. 25, 1934. If switch indication relay 1NKP is energized, its contact 128, shunting contacts 116 and 117 permits relay 1NWS to be energized over its pickup circuit including contact 9 when relay 1D is operated, even though relay 1MP or 3MP is deenergized. Relay 1D may thus be freely operated to control the signals 2 for the lower track, or to pick up relay NWS, so long as switches 1 and 1A are left normal, but relay 1NWS will be released without energizing relay 1RWS if the operator attempts to reverse the switches before the approaching train passes the signal to initiate the release of the approach locking.

Assuming that delivery relay 1D is operated when selector contact 10 is closed and relay L2LO deenergized, the signal control relay L2HS will become energized over a circuit from terminal B, contacts 10, 129, back contact 130, relay L2HS to terminal C, and will be held energized after relay 1D releases by its stick circuit including contacts 131, 132, 133 and 134. Relay L2HS may be released manually by operating relay 1D while contact 10 is open, and will be released automatically by the opening of contact 132 when a train enters section 1T, and may then be reenergized while section 1T is occupied as soon as relay 1TZ releases to shunt contact 132 by its back contact 135 to reestablish the stick circuit. Relay R2HS is similarly controlled by contacts 131 and 136 of relay 1D, selector contact 12 and contact 137 of relay R2LO.

The switch and signal control relays for switch 3 and signals 4 are controlled by a delivery relay 3D and are shown at the right in Fig. 11, the circuits for these relays being similar to those already described as will be apparent from the drawings.

Considering now the lockout relays LO, if the crossover is reversed and relay L4HS has been picked up and signal LC4 or arm b of signal L4 has been cleared, it is apparent from Fig. 10 that relay R2LO will be energized, and if relay 1D is then operated for the purpose of clearing the opposing signal R2, the energization of relay R2HS is prevented because back contact 137 of relay R2LO in the pickup circuit of relay R2HS is open, and consequently, the closing of a connection from terminal B to the network circuit of Fig. 10 to interfere with the energization of relay L4HX is prevented. Similar conditions prevail if the signal for the opposite direction over the same route is cleared, in which case relays R2HS and L4LO will be energized and the energization of relay L4HS will be prevented. If, now, the crossover is normal and relay L2HS has been picked up and signal L2 cleared, relay R2LO will be picked up to open its back contact 137 in the pickup circuit of relay R2HS. Since relay R2HS is controlled by the same relay, namely, relay 1D, as relay L2HS, the operation of relay 1D with selector contact 12 closed, will open contact 131 in the stick circuit of relay L2HS, but a circuit is now closed which may be traced from terminal B, contacts 12, 136, front contact 75

137 of relay R2LO, contacts 132, 133, 134, relay L2HS, to terminal C, so that relay L2HS is prevented from releasing due to an attempt to pick up relay R2HS. Relay L2HS may, of course, be released to put signal L2 manually to stop by operating relay 1D to open contact 131 when contacts 10 and 12 are both open. Each of the remaining relays in Fig. 11 are controlled in a similar manner, as will be apparent from the drawings.

With all of the apparatus in the normal condition as shown in the drawings, it will be evident that the operator is free to reverse the switches and to clear any of the signals. To explain the operation of the system, however, I will first assume that the switches are left normal and the operator transmits a code to clear arm *a* of signal R2 to permit a train to move from left to right over the lower main track. The effect of the code will be to close contacts 9 and 12 and to pick up relay 1D momentarily, relay 1NWS remaining energized and relay R2HS picking up to close contacts 91 and 92 shown in Fig. 10. Relay 1NKZ being energized, relays R2HX and 2. L2LO will now pick up in series. Relay R2HX closes contacts 64 and 68, shown in Fig. 9, to energize signal relay RA2H. Relay RA2H upon becoming energized closes contact 161 of Fig. 8 to light the green lamp G for arm *a* of signal R2 and also opens back contact 46 to deenergize relay R2M of Fig. 6, which releases in turn to lock switches 1 and 1A normal by the opening of contact 20 in the circuit for relays 1WR and 1AWR of Fig. 4, and also opens contact 109 to release relay 1MP of Fig. 12.

Referring to Fig. 11, it will be noted that the operator is now prevented from effecting any control by the operation of relay 1D other than to return the cleared signal to stop. Thus an attempt to reverse switches 1 and 1A by operating relay 1D when contact 11 is closed and contact 9 is open results merely in releasing relay 1NWS without energizing relay 1RWS, because contact 124 of relay 1MP in the pickup circuit for relay 1RWS is open. An attempt to clear the opposing signal L2 by operating relay 1D when contact 10 is closed and contact 12 open is without effect, relay L2HS being prevented from picking up because back contact 130 of relay 2. L2LO in its pickup circuit is open, while relay R2HS is prevented from releasing because when contact 131 of relay 1D is open it is bridged by a circuit including front contacts 10, 129 and 130. It is to be noted however, that since this circuit includes contact 10, contact 131 will be effective to release relay R2HS in the event the operator sends a signal stop code operating relay 1D when contacts 10 and 12 are both open.

Arm *a* of signal R2 having been cleared, the operator may now operate switch 3 or clear any one of the signals governing the movement of traffic over the upper track with switch 1A normal. To clear arm *a* of signal L4, for example, he will transmit a code to close contacts 9 and 10 and to pick up relay 3D momentarily, relay 3NWS remaining energized and relay L4HS picking up to cause relays L4HX, R4LO and LA4H to become energized. Relay LA4H, by opening its contact 138 deenergizes relay R4M, which releases and opens its contacts 18 and 158, shown in Fig. 4, to lock switches 1, 1A and 3, and also opens its contact 108, shown in Fig. 12, to deenergize relay 3MP. The operator now has no control over the apparatus controlled by relay 3D other than to deenergize relay L4HS to put the

signal to stop, because contact 139 of relay 3MP in the pickup circuit of relay 3RWS is open, and back contact 140 in the pickup circuit of relay R4HS is open.

I will now assume that a train accepting signal R2 with arm *a* at clear, enters section 1T. Relay 1TR will release, opening contact 22 in the circuit of relays 1WR and 1AWR, opening contact 65 to release relay RA2H, opening contact 132 to release relay R2HS, opening contact 5 to release relay 1TZ, and opening contact 59, shown in Fig. 6, to prevent the initiation of an operation of relay 2TE when relay RA2H releases to close contact 46. Relay RA2H upon releasing also closes back contact 161 to light lamp R to cause signal R2 to indicate stop. Relay R2HS upon releasing opens its stick contact 141 and also opens contacts 91 and 92, in the route network to release relay R2HX, which relay in turn opens contacts 64 and 68, in the signal network to release relay RA2H, so that the signal will remain at stop after the train leaves section 1T and until it is again manually governed. Relay 1TZ upon releasing opens its contact 23 in the circuit of relays 1WR and 1AWR, and closes its back contact 112 in the circuit of relay 1MP, but this relay will not pick up to close contacts 116 and 124 in the pickup circuits of relays 1NWS and 1RWS at this time because signal L4 has been cleared and contact 103 of relay L4M is open. Relay 1TZ also closes back contact 135 in the stick circuits of relays L2HS and R2HS. As soon as the train occupying section 1T enters section 2T, relay 2TR will release, completing the pickup circuit for relay R2M including back contacts 52 and 54 so that relay R2M will pick up. Relay 2TR also opens contact 66, shown in Fig. 9, in the circuit for relay RA2H, so that if relay R2HS is again energized the signal will not clear until the train vacates section 2T.

If, now, a second train accepts signal L4 and enters section 3T, relays L4HS and 3TZ will become deenergized to initiate a sequence of operations similar to those just described, and as soon as relay 3TZ releases the closing of its back contact 111 will cause relays 1MP and 3MP to pick up. Since relay L2LO is released, the switch and signal control relays governed by relay 1D are fully restored to the control of the operator. It follows that as soon as a train passes a signal and a relay TZ releases, relays L2HS and R2HS are rendered responsive to codes for clearing the signals so that the operator may send a new code to clear the same signal or a different signal governed by the same relays and the code will be "stored" by one of these relays until conditions are favorable for clearing the signal. Furthermore, since the switch control relays 1NWS and 1RWS are also rendered responsive to codes, it will be apparent that the operator may at the same time send a new code to operate the switch provided either the approach locking associated with other signals governing traffic over the same switch is released or the corresponding track sections are occupied. This switch operating code will then be "stored" by one of the switch control relays, and just as soon as conditions become favorable for the operation of the switch so that the switch locking becomes fully released, the switch will operate automatically without further attention upon the part of the operator.

I will next assume that with section 3T occupied, the operator transmits a code in which relay 3D is operated while contacts 11 and 10 are closed, so as to pick up relays 3RWS and L4HS

for the purpose of reversing switch 3 and of clearing signal LC4 for a train movement from the siding through sections 3T and 4T. When relay 3D picks up, however, the first result will be to release 5 relay 3NWS which will open contact 38, shown in Fig. 5, to quickly release relay 3KZ, which relay in turn will open contact 102 in the route network so that when front contacts 104 and 103 of relay 10 R4HS close, relay R4HX will not pick up. When the train in section 3T enters section 4T, the pickup circuit for relay L4M will become closed 15 over contacts 138, 142 and 143, so that relay L4M will pick up to close contact 158 in the circuit of relay 3WR. Relay 3WR will become energized 20 in the reverse direction over the circuit including front contact 27 of relay 3RWS and back contact 26 of relay 3NWS as soon as the train passes entirely out of section 3T and relays 3TR and 25 3TZ pick up to close contacts 144 and 145. Relay 3WR will then reverse its contacts to energize the switch motor of the switch machine 3SM to reverse the switch, and when switch 3 completes its movement to reverse, relay 3KR will become energized in the reverse direction and relays 3KRP and 3KZ will pick up, relay 3KZ closing 30 contact 102 so that relays L4HX and R4LO will pick up in series. Relay L4HX will now close contacts 75 and 80 in the signal network, and contact 81 of relay 3RKP also being closed, relay 34 LC4H will pick up, clearing signal LC4, and by opening its back contact 146 releasing relay L4M to open contacts 17 and 151 to lock the switches, relay L4M also opening contact 108 to release relays 1MP and 3MP. It will be apparent from 35 Fig. 8 that since the switches are normal, the normal switch indication relays 1NKP and 3NKP are energized, and that contacts 128 and 152 of these relays shown in Fig. 10, are closed, so that the normal switch control relays 1NWS and 3NWS 40 remain responsive to codes. The contacts of the reverse indication relays 1RKZ and 3RKZ will be open, however, and since contact 124 of relay 1MP and contacts 125 and 139 of relay 3MP are also open, relays 1RWS and 3RWS are non-45 responsive to codes.

I will now assume that the operator forgets that signal LC4 is at clear and attempts to clear arm b of signal R2 by operating relay 1D with selector contacts 11 and 12 closed. When relay 1D picks 50 up, contact 120 opens to release relay 1NWS, and relay 1NKZ releases to open contact 94 in the route network. Contact 105 of relay 1RKZ being also open, it follows that relay R2HX will not become energized when relay R2HS picks up. Relay 1RWS will not pick up when relay 1D is operated because relay 1MP is deenergized.

In this instance, it will be evident that if the signal network circuits of Fig. 9 were controlled directly by the signal control relays, switch 1 being locked normal, the energization of relay R2HS would have cleared arm a of signal R2, and the train would have been directed into a route different from the intended route. This can not happen when the signals are controlled as here-60 in disclosed because the route relays HX inter-65 posed between the signal control relays and the signals become energized only when each switch of a route and its switch control means are in corresponding positions.

70 Furthermore, in the case just described, when relay 1NKZ releases to prevent the improper clearing of arm a of signal R2, its contact 100 in the route circuit previously closed to clear signal LC4 also opens, but relay L4HX will then 75 be held energized over its stick circuit including

contact 147 and resistor 148 so that signal LC4 will not be interfered with.

It is to be understood that the usual indication lamps are provided in the dispatcher's office to indicate the condition of the relays KR and of 5 the signal relays H, so that when a switch or signal fails to respond to its manual control the operator will be informed of the fact. In the case described, as soon as the operator finds that signal R2 can not be cleared, he will restore the 10 apparatus to its former condition by transmitting a code to pick up relay 1NWS, this being possible because contact 128 of relay 1NKP in the pickup circuit of relay 1NWS is closed.

I will next assume that the operator transmits 15 a code in which relay 3D is operated when contacts 10 and 12 are both open, in order to release relay L4HS to put signal LC4 to stop. When relay 3D is operated, relay L4HS will release, releasing relay L4HX, and then relay LC4H will 20 release to close its back contact 146, shown in Fig. 6, thereby energizing the time element relay 4TE to pick up relay L4M at the end of a predetermined time interval. Since relay L6M has a front contact 82 in the signal network of Fig. 9 25 in the circuit of relay R4H, and front contacts 17 and 151 in the circuits of relays WR, it is clear that the immediate clearing of the opposing signal R4 or the immediate reversal of switches 1 and 1A or of switch 3 will be prevented 30 when signal LC4 is put to stop manually.

I will now assume that the apparatus is in the normal condition as shown in the drawings, and that the relays 1D and 3D are both operated to reverse both the crossover and switch 3 to 35

clear arm b of signal R2 for a train movement from left to right from section A2T to the siding. In this instance, relay 1D will be operated when contacts 11 and 12 are closed and relay 3D will be operated when only contact 11 is closed. 40 When relay 1D operates, relay 1NWS will release and relays 1RWS and R2HS will pick up and when relay 3D operates, relay 3NWS will release and relay 3RWS will pick up. Relays 1NKZ and 3KZ will thus be released by the opening of contacts 38 and 42, as shown in Fig. 5, and since all of the approach locking relays are energized and the switch sections are unoccupied, the switches will be unlocked so that relays 1WR, 1AWR and 3WR will be operated to reverse, en- 45 ergizing the switch motors in the reverse direction to move the switches to reverse. Contact 40 of relay 3RWS shown in Fig. 5 being closed, relay 3KZ will then be reenergized because when switch 3 reverses relay 3RKP becomes energized 50 to close contact 41, and relay 1RKZ will likewise become energized when the crossover re- 55 verses. Contacts 91 and 92 of relay R2HS being closed, relay R2HX will become energized as soon as contacts 102 and 105 of relays 3KZ and 1RKZ 60 close, that is to say, as soon as each switch of the route has been operated to the position corresponding to that of its switch control means, and relay L4LO will become energized in series with relay R2HX. When relay R2HX picks 65 up, its contacts 64 and 68 in the signal network, Fig. 9, will close, and since contacts 84 and 86 of relay 1RKP are closed and the corresponding contacts 63 and 67 of relay 1NKP are open, relay R2H will become energized to clear arm b 70 of signal R2. Since relay L4LO is energized in series with relay R2HX, the operator will be unable to energize relay L4HS if he attempts to clear the opposing signal LC4, and operates relay 3D when contact 10 is closed, because back 75

contact 149 of relay L4LO in the pickup circuit of relay L4HS will be open. Furthermore, any operation of relays 1D and 3D for the purpose of restoring any of the switches to normal to set up other conflicting routes will result merely in the deenergization of the switch control relays RWS and the opening of the contacts of the relays KZ in the route network, this however being without effect upon the signal which has been cleared because relay R2HX will be retained energized over its stick circuit including contact 96. It is also clear that the operator will be unable to clear any conflicting signal because he will be unable to pick up any other HX relay.

15 In the case just described, when relay RB2H picks up contact 47 will open to release relay R2M. Relay R2M upon releasing locks the crossover reversed by opening contact 29 in the circuit for relays 1WR and 1AWR, and also opens contact 57 to release the section locking relay 3S, shown in Fig. 7, and opens contact 109 to release relay 1MP. Relay 3S, upon releasing, locks switch 3 reversed by opening contact 150 in the circuit for relay 3WR and also opens contact 113 to release relay 3MP. When the train accepting signal R2 enters section 1T and relay 1TZ releases, its back contacts 112 and 114 close and relays 3MP and 1MP are reenergized to condition the switch control relays to receive any codes that the operator may transmit to set up a new route. The switches being locked, this code will be "stored". Relay R2M will pick up when the train enters section 3T and relay 3TZ closes its back contact 55. Relay 3S will pick up when the train passes out of section 1T and relay 1TR closes its front contact 60, and the switch locking will be released to permit the relays WR to be operated just as soon as the train passes out of section 3T and relay 3TZ closes its front contacts 24 and 145.

Assuming next that signal LC4 is cleared for a movement in the opposite direction over the same route as in the preceding example, it will be noted that the switches will be locked by relay 45 LAM instead of by relays R2M and 3S, and that the locking of switch 3 will be released as soon as the train, moving toward the left, passes out of section 3T, while switches 1 and 1A will be locked reverse until the train passes out of section 1T.

50 In illustrating my invention I have assumed that each switch or crossover and the associated pair of opposing signals will be controlled by the same code and by a single relay D. It is obvious, however, that individual codes or direct wire control may be employed interchangeably, and that relays 1NWS and 1RWS may for example be controlled by one relay D and relays L2HS and R2HS by another relay D. This is because the arrangement of the apparatus of my invention is such that these relays D may be operated at any time whatsoever and the control relays will respond to their manual control only when conditions are favorable for their operation, with the single exception that codes may be "stored" after a train enters a switch section to become effective after it vacates the switch section. Furthermore, by reason of this "storing" of codes, my system provides for the prompt operation of the switches and signals under congested traffic conditions and therefore permits utilization of the maximum traffic capacity of the track layout.

75 While I have, in the foregoing, illustrated my system by reference to a relatively simple track layout, it will be clear that the same principles can be applied to complicated layouts involving

large numbers of traffic routes and that the system of my invention provides relatively simple and reliable apparatus for safely controlling interlocked railway track switches and signals from a remotely located office or cabin, in such a manner that a train can not be run over a route different from the intended route due to failure of a switch to respond to an operation of its control means and likewise that my system is so arranged as to provide a maximum degree of protection against interference with the movement of traffic when a signal has been cleared for an approaching train.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a traffic route including a plurality of railway track switches, a signal at each end of the route to govern the movement of traffic in opposite directions over the route, manually controllable switch control means for controlling the operation of each switch of the route, a signal control relay and a route relay for each signal, a pickup circuit for each route relay closed when the associated signal control relay is energized provided each switch of the route agrees as to position with its switch control means and the signal control relay for the opposing signal is deenergized, a stick circuit for each route relay controlled by the associated signal control relay only, and a circuit for clearing each signal controlled by each switch of the route and closed only when the associated route relay is energized and the route relay for the opposing signal is deenergized.

2. In combination, a traffic route including a plurality of railway track switches, a signal at each end of the route to govern the movement of traffic in opposite directions over the route, manually controllable switch control means for controlling the operation of each switch of the route, a signal control relay and a route relay for each signal, an energizing circuit for each route relay closed only when the associated control relay is energized provided each switch of the route agrees as to position with its control means and the control relay for the opposing signal is deenergized, means preventing the release of each route relay when the associated control relay is energized if said energizing circuit is opened by the operation of the switch control means for a switch of said route, a circuit for clearing each signal controlled by each switch of the route and closed only when the corresponding route relay is energized, and means preventing the operation of any switch of said route in response to the operation of its control means when one of said signals has been cleared.

3. In combination, a traffic route including a plurality of railway track switches, two opposing signals including one at each end of the route to govern the movement of traffic in opposite directions over the route, manually controllable switch control means for controlling the operation of each switch of the route, a manually controllable signal control relay and a route relay for each signal, a pickup circuit for each route relay closed when the associated signal control relay is energized and the opposing signal con-

trol relay is deenergized provided each switch of the route agrees as to position with its switch control means, a stick circuit for each route relay controlled by the associated signal control relay 5 only, and a circuit for clearing each signal closed when the associated route relay is energized and the opposing stick relay is deenergized provided the switches are positioned to establish said route and the opposing signal is deenergized.

10 4. In combination, a traffic route including a plurality of railway track switches, switch control means for each switch of the route, a manually controllable signal control relay, a route relay, a pickup circuit for said route relay closed 15 only when the signal control relay is energized and each switch of the route agrees as to position with its control means, a stick circuit for said route relay closed when said route relay is picked up and the signal control relay is energized, a signal for governing the movement of traffic over said route, and a circuit for clearing the signal closed only when said route relay is energized.

5. In combination, a traffic route including a plurality of railway track switches, switch control means for each switch of the route, a manually controllable signal control relay, a route relay, a pickup circuit for said route relay closed only when the signal control relay is energized and 30 each switch of the route agrees as to position with its control means, a stick circuit for said route relay closed when said route relay is picked up and the signal control relay is energized, a signal for governing the movement of traffic over said route, 35 an operating circuit for each switch of the route controlled by the corresponding switch control means and closed only when said signal is in its most restrictive condition and a circuit for clearing the signal closed only when said route relay 40 is energized.

6. In combination, a traffic route including a plurality of railway track switches, manually controllable switch control means for each switch of the route, a manually controllable signal control relay, a route relay controlled by said signal control relay, means effective when the manually controllable switch control means for each switch of the route has been operated and said signal control relay has been energized for preventing 45 the energization of said route relay until each switch of the route assumes a position corresponding to that of its switch control means, a signal for governing the movement of traffic over said route, and means controlled by said route relay and by each switch of the route for controlling said signal independently of the condition 50 of said switch control means.

7. In combination, a traffic route including a railway track switch, a signal at each end of the 60 route to govern the movement of traffic in opposite directions over the route, manually controllable switch control means for controlling the operation of the switch, a manually controllable signal control relay for each signal, a route relay, 65 and a lockout relay for each signal control relay, a circuit for energizing each route relay and the corresponding lockout relay in series including a front contact of the associated signal control relay and a back contact of the signal control relay for the opposing signal, said circuit also including contacts closed only when the switch and its control means are in corresponding positions, a circuit for clearing each signal closed when the corresponding route relay is energized, and means 70 controlled by each lockout relay effective to pre-

vent the signal control relay for the opposing signal from becoming energized when such lockout relay is energized.

8. In combination, a traffic route including a railway track switch, two opposing signals including one at each end of the route to govern the movement of traffic in opposite directions over the route, manually controllable switch control means for controlling the operation of the switch, a manually controllable signal control relay and 10 a route relay for each signal, a pickup circuit for each route relay closed only when the associated signal control relay is energized and the opposing signal control relay is deenergized provided the track switch agrees as to position with its 15 control means, a stick circuit for each route relay controlled by the associated signal control relay only, means rendered effective when either of said route relays is energized to prevent the energization of the signal control relay for the 20 opposing signal, and a circuit for clearing each signal closed only when the associated route relay is energized.

9. In an interlocking system for railroads, a traffic route including a plurality of railway track 25 switches, a signal to govern the movement of traffic over said route, a route relay for controlling said signal, a remote controlled switch control relay for each switch, means controlled by each switch controlled relay for controlling the 30 corresponding switch, a remote controlled signal control relay, a pickup circuit for said route relay controlled by said signal control relay and by the switch control relay for each switch of the route, a stick circuit for said route relay controlled by said signal control relay only, and a circuit for clearing said signal controlled by each 35 switch of the route and closed only when said switches are in position to establish said route and said route relay is energized. 40

10. In combination with a railway track switch, a route network comprising a first conductor having one end connected to the adjacent end of a second conductor when the switch is normal and to the adjacent end of a third conductor 45 when the switch is reversed, a signal for governing the movement of traffic over said switch associated with each conductor, a control relay for each signal, a plurality of lockout relays including one for each conductor each connected to the free end of such conductor over a back contact of the associated control relay and to one terminal of a source of current, a plurality of route relays including one for each conductor each connected to the free end of such conductor and 50 to the other terminal of said source over front contacts of the associated control relay, a manually governed circuit for each control relay including a back contact of the associated lockout relay, and a control circuit for each signal including 55 a front contact of the associated route relay.

11. In combination with a railway track switch, two signals, one for each position of the switch, for governing the movement of traffic over 65 the switch, signal control means including selecting means for selecting one signal or the other for clearing in accordance with the position of the track switch and also including a relay for clearing the selected signal, remote control means 70 for operating said selecting means and said relay, a locking relay which becomes deenergized when either signal is cleared and which remains deenergized when such signal is manually put to stop provided there is a train approaching within a 75

predetermined distance of the signal, a normal circuit and a reverse circuit for rendering said selecting means responsive to the operation of said remote control means, each including a contact 5 which opens when said locking relay is deenergized, and means controlled by the track switch for bypassing the locking relay contact in the normal circuit when the switch is normal and for bypassing the locking relay contact in the 10 reverse circuit when the switch is reversed.

12. In combination with a railway track layout including a plurality of track sections interconnected by track switches, a route circuit network, contacts controlled by the track switches for controlling said network to establish different route circuits, there being one route circuit for each traffic route through the track layout, signals for governing traffic movements through the layout including one for each direction for each traffic route, a control relay, a route relay and a lock-out relay for each signal, an energizing circuit for each control relay including a back contact of the lock-out relay for the same signal, a pickup circuit and a stick circuit for each route relay each including its winding and a front contact of the control relay for the same signal, each pickup circuit also including the route circuit for the corresponding traffic route and the winding of the lock-out relay for the opposing signal for the same route, and a circuit for clearing each signal each said circuit including a front contact of the route relay for such signal.

13. In combination with a railway track layout including a plurality of track sections interconnected by track switches, a route circuit network, contacts controlled by the track switches for controlling said network to establish different route circuits, there being one route circuit for each traffic route through the track layout, signals for governing traffic movements through the layout including one for each direction for each traffic route, a control relay and a lock-out relay for each signal, a control circuit for each signal control relay including the route circuit for the corresponding traffic route, the winding of the lock-out relay for the opposing signal for the same route and means controlled by the associated lock-out relay, and means controlled by each control relay for clearing the corresponding signal.

14. In combination with a railway track layout including a plurality of track sections interconnected by track switches, a route circuit network, contacts controlled by the track switches for controlling said network to establish different route circuits, there being one route circuit for each traffic route through the track layout, signals for governing traffic movements through the layout including one for each direction for each traffic route, a control relay, a route relay and a lock-out relay for each signal, an energizing circuit for each control relay including a back contact of the lock-out relay for the same signal, an energizing circuit for each route relay including its winding and a front contact of the control relay for the same signal each such circuit having a first branch including the route circuit for the corresponding traffic route and the winding of the lock-out relay for the opposing signal for the same route and a second branch including a front contact of the route relay, current limiting means included in said second branch so proportioned as to maintain the route relay energized when the route circuit is open and to maintain the lock-out relay energized when the route circuit is closed, and a circuit for clearing

each signal including a front contact of the route relay for such signal.

15. In combination with a railway track layout including a plurality of track sections interconnected by track switches, a route circuit network, contacts controlled by the track switches for controlling said network to establish different route circuits, there being one route circuit for each traffic route through the track layout, signals for governing traffic movements through the layout including one for each direction for each traffic route, a lock-out relay for each signal, normally connected to the adjacent end of the route circuit for such signal, a control circuit for each signal including the route circuit for the corresponding route and the winding of the lock-out relay for the opposing signal for the same route, control means for closing such control circuit effective only when the lock-out relay for the signal controlled thereby is deenergized, and means controlled by said control means when operated for disconnecting the last named lock-out relay from its route circuit.

16. In a centralized traffic control system for railroads, two signals for governing the movement of traffic in opposite directions over the same route, a control relay and a lock-out relay for each signal, a pickup circuit for each control relay including a normally open code-controlled contact and a back contact of the associated lock-out relay, a stick circuit for each control relay including a normally closed code-controlled contact, a route relay for each signal for controlling such signal, and an energizing circuit for each route relay controlled by the associated control relay and including the winding of the lock-out relay for the opposing signal.

17. In a centralized traffic control system for railroads, two signals for governing the movement of traffic in opposite directions over the same route, a stick control relay, a route relay and a lock-out relay for each signal, code-controlled means for picking up and for releasing said control relay, an energizing circuit for each route relay including its winding, a front contact of the associated control relay and the winding of the lock-out relay for the opposing route relay, an energizing circuit for each signal including a front contact of its route relay and a back contact of the route relay for the opposing signal, and means preventing the energization of said route relay when the lock-out relay for the same signal is energized.

18. In a centralized traffic control system for railroads, two signals for governing the movement of traffic in opposite directions over the same route, a control relay and a lock-out relay for each signal, a pickup circuit for each control relay including a normally open code-controlled contact and a back contact of the associated lock-out relay, a stick circuit for each control relay including a normally closed code-controlled contact, a second stick circuit for each control relay including said normally open code-controlled contact and a front contact of the associated lock-out relay, a route relay for each signal for controlling such signal, and an energizing circuit for each route relay controlled by the associated control relay and including the winding of the lock-out relay for the opposing signal.

19. In a centralized traffic control system for railroads, a track layout including a plurality of track switches, a plurality of signals for each direction for governing the movement of traffic

through said layout, a control relay and a lock-out relay for each signal, a pick-up circuit for each control relay including a code-controlled contact and a back contact of the associated lock-out relay, a stick circuit for each control relay including a normally closed code-controlled contact, a route relay for each signal for controlling such signal, and an energizing circuit for each route relay controlled by the corresponding control relay 5 in accordance with the positions of said track switches and closed only when the route governed by the signal which such route relay controls has been established, said energizing circuit also including the winding of the lock-out relay for the signal for the opposite direction for the same route.

20. In a centralized traffic control system for railroads, a track layout comprising two parallel tracks connected by a crossover, a plurality of

signals including one for each direction for each track for governing the movement of traffic over different routes through said layout, switch control means for operating the switches of said crossover, a signal control relay for each signal, a route relay for each signal for controlling such signal, a pickup circuit for each route relay controlled by the corresponding control relay and by said switch control means and closed only when the switches and the switch control means occupy 10 corresponding positions and the position of the switches is such as to establish the route governed by the signal which such route relay controls, a stick circuit for each route relay controlled by the corresponding control relay only, and means rendered effective when a route relay is energized to prevent the clearing of the opposing signal for the same route. 15

EARL M. ALLEN.

DISCLAIMER

2,046,049.—*Earl M. Allen*, Swissvale, Pa. RAILWAY TRAFFIC CONTROLLING APPARATUS. Patent dated June 30, 1936. Disclaimer filed March 21, 1939, by the assignee, *The Union Switch & Signal Company*.
Hereby disclaims the subject matter of claims 1, 3, 9, and 20 in said patent.
[*Official Gazette April 18, 1939.*]
